UNITED STATES PATENT OFFICE.

EDWARD P. CHALFANT, OF KENOSHA, WISCONSIN.

DESIGN FOR A JAW FOR SEAT-CLAMPS FOR BICYCLES.

SPECIFICATION forming part of Design No. 26,738, dated March 9, 1897.

Application filed November 16, 1896. Serial No. 612,367. Term of patent 7 years.

To all whom it may concern:

Be it known that I, EDWARD P. CHALFANT, a citizen of the United States of America, residing at Kenosha, in the county of Kenosha 5 and State of Wisconsin, have invented a new and original Design for a Jaw for a Seat-Clamp for Bicycles, of which the following is a specification, reference being had to the accompanying drawings, of which—

10 Figure 1 is an end view, and Fig. 2 a side view, of my design.

Looking at the drawings, a jaw designed for use in a seat-clamp for bicycles is seen, shaped in end elevation to a circular portion a , at the 15 bottom inclosing a round open space, and extending upward from said circular portion in the form of a substantially semicircular arc a' , from the top of which is a still further extension a^3 , which curves back upon itself 20 at a^4 and extends downward substantially to the convex side of the portion a' at a^5 , at which point the lower end of said extension is concave outwardly and convex upon the side adjacent to the semicircle a' , the portions $a' a^3 a^4$ inclosing an open space, and all 25

of the portions described being of substantially equal thickness. The outline of my invention as disclosed in the side elevation I consider to be immaterial; but the preferred form is shown in Fig. 2, said outline having 30 straight parallel edges, square corners, and a downward extension a^2 at the bottom, the outline of which, disclosed in this view, is also square-cornered.

The essential features of my design I consider to be the approximately uniform thickness of the same in end elevation, the semicircular arc-shaped portion a' , the upward extension a^3 and return a^4 , substantially inclosing an open space, and the outwardly-concave termination a^5 of the return a^4 . 35 40

I claim as new and desire to secure by Letters Patent—

The design for a jaw for a seat-clamp for bicycles, substantially as shown and described. 45

EDWARD P. CHALFANT.
